TRACTOR ROLL-OVER PROTECTION FRAME

William F. H. Purcell, New York, James M. Conner,
Mamaroneck, and Charles W. Pelly, Scarsdale, N.Y.,
assignors to Deere & Company, Moline, Ill.

Filed Mar. 22, 1972, Ser. No. 237,227

Term of patent 14 years

Int. Cl. D12—09

U.S. Cl. D40—5

FIG. 1

FIG. 2

FIG. 3

FIG. 1 is a side and partial front perspective view of our design for a tractor roll-over protection frame, the opposite side being substantially a mirror image thereof.

FIG. 2 is a front perspective view thereof.

FIG. 3 is a rear perspective view thereof.

We claim:

The ornamental design for a tractor roll-over protection frame, substantially as shown.
